CLAIM

The ornamental design for a window component extrusion, as shown and described.

DESCRIPTION

FIG. 1 is a right side perspective view of a window component extrusion showing our new design, the center being broken away to indicate indeterminate length; FIG. 2 is a left side perspective view thereof;

FIG. 3 is a right side perspective view of a second embodiment of a window component extrusion showing our new design; and, FIG. 4 is a left side perspective view thereof.

FIG. 1

FIG. 2

FIG. 3

FIG. 4
